UNITED STATES PATENT OFFICE.

GEORGE COLVIN KENNEDY, OF WATERLOO, IOWA.

MARBLE-SHOOTER.

1,266,276.

Specification of Letters Patent. Patented May 14, 1918.

Application filed January 5, 1915, Serial No. 661. Renewed October 12, 1917. Serial No. 196,344.

To all whom it may concern:

Be it known that I, GEORGE COLVIN KENNEDY, a citizen of the United States of America, and a resident of Waterloo, Black-hawk county, Iowa, have invented certain new and useful Improvements in Marble-Shooters, of which the following is a specification.

My invention relates to improvements in marble-shooters, and the object of my improvement is to provide children with an implement for propelling marbles in the game of that kind, which implement or propelling means can be conveniently used either in making drop or rolling shots, and which can be sighted accurately.

A further object is to improve the form and construction of my marble-gun or shooter patented in the United States under Patents Nos. 1,037,262 and 1,077,142.

These objects I have accomplished by the means which are hereinafter described and claimed, and which are illustrated in the accompanying drawings, in which:

Figure 1 is a side elevation of my improved marble-shooter, with the standards thereon arranged to serve as sighting-means.

Fig. 2 is a side elevation of said device, inverted, with the standards brought together to be used as a handle.

Fig. 3 is a right-hand end elevation of said device in the position indicated in said Fig. 2, and Fig. 4 is a cross-section of the device taken on the line *a*—*b* of Fig. 2.

Fig. 5 is a view, partly in plan and partly in perspective, of the leather marble clip and one of the pair of elastic bands connected thereto.

Fig. 6 is a side elevation of an alternative form of my improved marble-shooter.

Fig. 7 is an end elevation of the same.

Fig. 8 is a view of the body of my device, as developed on a plane surface.

Similar numerals of reference denote corresponding parts throughout the several views.

My improved marble shooter comprises a tube 1, formed of a single plate bent into a hollow cylinder with its longitudinal edges meeting, and having opposite parts removed to provide finger clearance spaces 5.

The numerals 14 and 15 denote like rings formed from strips of material bent circularly, secured by rivets 10 and 12, passed through the ends 9 and 16 and 11 and 17, respectively, and having the longer ends 9 and 11 extending outwardly to form like standards. These rings are fitted upon the cylinder 1, slidably.

The numeral 6 denotes slots placed in opposite sides of the delivery end of said cylindrical tube, and elastic endless rubber bands 7 may be secured in said slots to extend alongside the tube nearly to the openings 5.

In Fig. 5 is shown a strip 8 of flexible material, which may be of thin leather or other material, and whose ends are fashioned into double-ears or tabs 20 separated by narrow necks 19. Each end of the strip has a perforation 18 just within said neck. The strip 8 has a central orifice 35 in which is secured an annulus 36 to prevent rupture of the strip at this place. Each band 7 is secured to an end of said strip 8 by being looped about the neck 19 and then passed through the perforation 18 before being secured in the slot 6 of said tubes. When said parts have thus been assembled and secured to the tube 1, the strip 8 will span the hollow of the tube between the troughs 3 and 4 on upper and lower sides of the openings 5, and will be held there by the tension of the slightly stretched rubber bands 7.

The delivery-end of the tube 1 may be indented outwardly at a place opposite the alinement of the standards 9 and 11, when in the positions indicated in Fig. 2, to afford a sight when the device is used for a drop-shot, and when said standards have been brought together to form a handle underneath the tube. When it is desired to use the device for a rolling shot, the tube 1 is reversed, and the standards 9 and 11 spread apart, as shown in Fig. 1, the gun then being placed flatly on the ground or other supporting surface, so that the user may look across the standards to get them in alinement with the object or marbles to be aimed at. The gun is loaded by depositing the marble in the delivery-end of the tube, letting it down to the strip 8, and when it is over the perforation 35, which lat-

ter insures its being centrally placed on the strip in a balanced position as regards the bands 7, the user can then grasp the strip on opposite sides of the contained marble 5 and draw it back as far as necessary to secure the desired tension in the bands 7, as indicated by the dotted lines in said Fig. 1. When properly sighted, the projectile marble may be released for either a drop or 10 a rolling shot, according to the manner in which the gun is handled. Since the projectile marble is held in the flexible strip 8 between the finger and thumb of the player, located correctly over the central perforation 35, with both bands 7 under equal tension, the marble may be propelled accurately 15 to its goal.

In Figs. 6, 7 and 8 is displayed a modified form of device, used in both modes hereinbefore described. In this form of the device the cylinder 23 and the standards 24 and 26 are integral, so as to be cheaply stamped out from a plate of metal at one stroke by dies, to produce the flat body shown in Fig. 8. 25 This body is rolled to form the tube 23 therefrom, with the spaced standards 24 and 26 projecting outwardly in alinement. The standard 24 may have an opening 25 to serve as a finger-grip when the gun is inverted as 30 in Fig. 6 for a drop-shot, in which case the standard 26 is also grasped firmly. On opposite sides of the plate are projections 28 and 27, so located that when the plate is rolled into a tube, the wider projection 27 35 may be bent and clenched over the projection 28 to secure the abutting edges of the tube together. The tube 23 has, opposite the said standards and on each end, the outwardly indented projections 29 and 30 for 40 fixed sights when the gun is held up for a drop-shot, but when the gun is inverted and laid on the ground the said standards serve as sights, being long enough to be convenient of access to the user when bending toward 45 the ground. In this form of the device, finger openings 31 are provided on opposite sides, preferably closed at both ends to strengthen the gun structure.

In this device 23, similar bands 33 are secured between orifices 32 in the tube and the ends of a flexible strip 34, but the closing in of the outer ends of the openings 31 permits these openings to be extended nearer the delivery-end of the tube, since the standards 55 24 and 26 do not interfere, and so the user may introduce the projectile marble into the delivery end of the tube with a finger to press both it and the inclosing strip 34 back far enough into the hollow of the tube as to 60 permit them to be readily grasped with the finger and thumb of the other hand through the openings 31. The projectile marble cannot escape from the tube except by way of its delivery end, and the upper and lower 65 troughed parts 3 and 4 of the tube serve to

give direction to the marble, as much as necessary to insure correct delivery.

Having described my invention, what I claim as new, and desire to secure by Letters Patent is:

1. In a device of the character described, a tube having oppositely-located longitudinal openings to serve as finger-clearance spaces between upper and lower troughed parts, a flexible strip passed through said openings 75 transversely, and yieldable resilient connections between opposite ends of said strip and the delivery end of said tube, opposite ends of the tube having parts projected outwardly integrally alined longitudinally to serve as 80 sighting-means.

2. In a device of the character described, a tube and spaced standards fixed thereon, the standards being alined longitudinally to serve either as sighting means, or as handles 85 when inverted, the endmost standard provided with a finger-hold, and projectile propelling means operatively associated with said tube.

3. In a device of the character described, 90 a tube having integral longitudinally alined standards extending angularly therefrom, said tube having oppositely-located longitudinal openings adapted to serve as finger clearance spaces at opposite sides of the 95 standards, and projectile actuating means movably located in the hollow of the tube and adapted to be propelled therethrough between said finger clearance spaces.

4. In a device of the character described, 100 a tube having longitudinally alined standards extending angularly therefrom, said tube having oppositely-located longitudinal openings adapted to serve as finger-clearance spaces at opposite sides of said standards, a flexible strip seated across the hollow of said tube, and like elastic endless-loop connections between the opposite ends of said strip and the opposite sides of the delivery end of said tube, the ends of said flexible strip being orificed and formed with terminal heads as securing-means for said looped connections.

5. In a device of the character described, a tube having longitudinally alined standards 115 extending angularly therefrom in one direction in longitudinal alinement and formed integrally from a single piece of material by being rolled cylindrically to bring its longitudinal edges together, and said tube having 120 means adapted to secure said edges together.

6. A device of the character described, comprising a plate rolled into tubular form with meeting longitudinal edges, spaced standards integrally extended outward from 125 one of said edges nearer one end of the tube than the other, in longitudinal alinement on the same side, said tube having oppositely located longitudinal finger-clearance openings near its end opposite its delivery end,

said tube having engaging means at its delivery end, a flexible strip located across the interior hollow of the tube with its ends extending outwardly through said finger-
5 clearance spaces and having engaging means at each end, and like elastic bands connected between the engaging means on the edges of said strip and the engaging means at the de-

livery end of the tube, said bands being under slight tension.

Signed at Waterloo, Iowa, this 21st day of December, 1914.

GEORGE COLVIN KENNEDY.
